[57] **CLAIM**

The ornamental design for a combined cover and countertop for cooler, as shown and described.

DESCRIPTION

FIG. 1 is a top plan view of a combined cover and countertop for a cooler showing my new design;

FIG. 2 is a front elevational view thereof, the rear elevational view being a mirror image thereof;

FIG. 3 is a right side elevational view thereof, the left side elevational view being a mirror image thereof;

FIG. 4 is an exploded top perspective view thereof, showing the cover member and the removable insert member;

FIG. 5 is a bottom plan view thereof;

FIG. 6 is a front elevational view of the removable insert member of FIG. 4, shown separately for clarity of illustration, the rear view being a mirror image thereof;

FIG. 7 is a right side elevational view thereof, the left side being a mirror image thereof;

FIG. 8 is an enlarged fragmentary cross-sectional perspective view thereof, taken on line 8—8 of FIG. 4; and

FIG. 9 is an enlarged fragmentary cross-sectional perspective view of the cover member of FIG. 4, taken on

line 9—9 of FIG. 4.
